UNITED STATES PATENT OFFICE.

CHARLES PARTELLO, OF WATERTOWN, NEW YORK.

IMPROVEMENT IN WINDOW-SASH FASTENERS.

Specification forming part of Letters Patent No. 133,050, dated November 12, 1872.

To all whom it may concern:

Be it known that I, CHARLES PARTELLO, of Watertown, in the county of Jefferson and State of New York, have invented certain new and useful Improvements in Sash-Fastenings; and I do hereby declare the following to be a full, clear, and exact description of the same, reference being had to the accompanying drawing forming part of this specification, in which—

Figure 1 is a perspective view of a window-sash, showing my improvements applied to the fastening; Fig. 2 is a side elevation of the same; and Fig. 3 is an edge view of the slotted guide and thumb-plate detached from the sash.

Similar letters of reference in the accompanying drawing indicate the same parts.

My invention relates to that class of sash-fastenings composed of a flat spring secured at one end in the edge of the sash, so as to hold a short stud upon its opposite end within a series of recesses in the window-casing. One end of a bent arm attached to the spring projects through a slot in the face of the sash, and forms a finger-piece which is grasped by the operator to withdraw the stud from the recesses and raise the sash. A face-plate of metal, slotted for the passage of the finger-piece, is sometimes affixed to the sash to prevent the finger-piece from wearing the wood. Inasmuch as the finger-piece is necessarily slight, it affords but a small point to be grasped by the fingers, and is liable to be broken upon a heavy sash or upon one that sticks or binds in its casing. The object of my invention is to afford a protector for the finger-piece, and at the same time an additional bearing or thumb-piece for lifting the sash. To this end it consists in constructing the face-plate with a diagonal thumb-piece at right angles, or nearly so, to the general direction of the slot, so that the operator, grasping the finger-piece and thumb-piece, shall press the former upward against the latter to

withdraw the locking-stud and raise the sash. By this means the strain upon the finger-piece is transferred to the thumb-piece, and the diagonal arrangement of the latter affords a strong wide purchase for raising the sash. A very slight finger-piece may therefore be used, sufficient only to operate the spring.

In the accompanying drawing, A is the window-sash; B, the flat spring secured at one end within the edge of the same, and carrying the locking-stud C at its lower end. D is the bent lever attached to the spring at or near its free end, projecting through a slot in the face of the sash, so as to form a finger-piece, E, as shown. These parts constitute the ordinary sash-fastening, and are not, therefore, of my invention. F is the metallic face-plate, cast with a wide diagonal thumb-piece, G, and with a curved slot, H, under the thumb-piece through which the finger-piece E projects. The general direction of the slot is at right angles, or nearly so, to the thumb-piece, and its upper end terminates at the lower side of the latter.

To unfasten and raise the window the operator grasps the pieces E G with the thumb and finger and pushes the finger-piece upward against the thumb-piece, which therefore sustains the whole weight of the sash while being raised, and relieves the finger-piece of all strain.

Having thus described my invention, what I claim is—

The metallic face-plate F, secured to the sash, and constructed with the diagonal thumb-piece E and slot H immediately beneath the thumb-piece, in combination with the bent arm D E and the spring-fastening B C, substantially as described, for the purpose specified.

CHARLES PARTELLO.
